UNITED STATES PATENT OFFICE.

CARL E. FORS AND FLOYD W. LILYARD, OF BURNSIDE, IOWA.

AUTOMATIC RAILROAD-SWITCH.

1,121,820.

Specification of Letters Patent. Patented Dec. 22, 1914.

Application filed March 7, 1914. Serial No. 823,576.

To all whom it may concern:

Be it known that we, CARL E. FORS and FLOYD W. LILYARD, citizens of the United States, and residents of Burnside, in the county of Webster and State of Iowa, have invented a certain new and useful Automatic Railroad-Switch, of which the following is a specification.

The object of our invention is to provide an automatic railroad switch of simple, durable and inexpensive construction.

More particularly it is our object to provide a railroad switch adapted to be automatically operated by approaching trains, and provided with simple means whereby the switch is held in either of its set positions so that it cannot be thrown without the exercise of considerable force.

Our invention consists in certain details, in the construction, combination and arrangement of the various parts of the device, whereby the objects contemplated are attained, as hereinafter more fully set forth, pointed out in our claims, and illustrated in the accompanying drawings, in which:

Figure 1 shows a top or plan view of a portion of the main line and switch track of a railroad track, equipped with an automatic switch mechanism, embodying our invention. Fig. 2 shows a side elevation of the operating arm mounted on ties which are shown in section. Fig. 3 shows a top or plan view of said operating arm. Fig. 4 shows a horizontal, sectional view through the pressure device, whereby our switch is held in either of its set positions. Fig. 5 shows a front elevation of one of the guide pulleys and tracks therefor, and Fig. 6 shows a top or plan view of a bar for operating the movable rail members and the parts immediately connected with said bar.

In the accompanying drawings, we have used the reference numeral 10 to indicate the rails of a main railroad track, and the numeral 11 to indicate the rails of the switch or side track. The rails 10 and 11 rest upon the usual ties. One rail member of the main track and one rail member of the switch track, indicated respectively by the numerals 10^a and 11^a are movable to be adjusted in the ordinary way for carrying a train from either of the tracks to the other.

Mounted between the free ends of the movable track members 11^a and 10^a is a plate 13. Pivoted to the plate 13, on each side thereof, are T shaped levers 14 and 15, hav-

ing the laterally extending arms A arranged at right angles to the rails of the switch track and the laterally extending arms B, arranged at right angles to the main track, and having the stems C and D respectively arranged parallel with the rails of the switch and main tracks. The members C and D are pivoted to a transverse bar 16 by means of a bolt 17 mounted in said bar and also mounted in elongated slots 18 in said stems. Secured to the ends of the laterally extending arms 15 are suitable devices 19 and 20 which may be chains, wires or the like, which extend along the main track between the rails, as shown in Fig. 1.

Suitably mounted on the ties of the main track at points spaced apart from the plate 13 a suitable distance, are brackets 21 centrally pivoted to which are bell crank levers 22 having curved arms 22^a and straight arms 22^b. The arm 22^a of one bell crank lever is secured to the member 20 and the arm 22^a of the other bell crank lever is secured to the member 19, as shown in Fig. 2. The arm 22 of each bell crank lever extends upwardly and toward the switch member 13 and is curved downwardly at the free end, as shown in Fig. 2.

Secured to the free ends of the laterally extending arms 14 are devices 23 and 24 and 24^a similar to the devices 19 and 20 which are extended along the switch track and main track respectively, as shown in Fig. 1, traveling over guide pulleys 25, suitably mounted on the ties, to similar devices 22^a, to which they are connected in the manner hereinbefore set forth.

It will be understood that the members 22 may be operated by a train moving in either direction so that, for instance, a train moving from the main track on to the switch track could, by engaging the member 22 connected with the member 24^a, close the switch after itself so that another train coming along on the main track would not be required to slow down to throw the switch.

Our improved switch device is designed to be used in combination with suitable engaging means mounted on the engine or car, whereby the arms 22 are engaged and depressed. It should be mentioned that the arms 22 on the main track are arranged at different distances from the respective rails and that the arms 22 of the switch track are arranged at different distances from the respective rails thereof. Each car or engine

is designed to be equipped with two engaging devices so arranged that they may be lowered or raised for engaging the arms 22 or not as desired.

It will readily be seen that if a train is approaching the switch on the main track from the left, as shown in Fig. 1, if an engaging device is lowered to engage the arm 22, connected with the member 19, the T-shaped device will move the bar 16 for moving the movable rail members and throwing the switch to position for causing the train to travel straight ahead on the main track. On the other hand, if the engaging device on the engine is lowered to engage the member 22, connected with the member 20, the switch will be turned or thrown to carry the train to the switch or side track. After the train has passed the switch, if it is desired to throw the switch to proper position to permit the next train to pass over the main track without moving the switch, the first train may, after passing the switch, throw the switch by means of the trip device connected with the member 24. In the same way, a train on the switch track approaching the main track, does not need to throw the switch if it is in the position shown in Fig. 1. If it is not in that position, the device 22 on the switch track may be struck by the engaging device on the train and the switch thrown to the position shown on Fig. 1. A train approaching the switch from the right, as shown in Fig. 1, will be required to strike the device 22 on the main track, thereby throwing the switch from the position shown in Fig. 1 to proper position for permitting the train to travel on the main track. For firmly holding the movable members 10^a and 10^b in position at either limit of their movement, we have provided the following means: Mounted on a suitable support at one side of the track, adjacent to the free ends of the members 10^a and 10^b is a cylinder 27, in which travels a piston 28 having a stem 29 extended through one end of said cylinder. Suitably pivoted to a support, near the cylinder 27, is a lever 30, one end of which is also pivoted to the stem 29, as shown in Fig. 4. Fixed to the rail 10^a at one end and pivoted to the lever 30 between its ends is a rod 31, on which are mounted stop devices 32. Mounted on the outer wall of the cylinder 27, near the ends of said cylinder, are brackets 33 and 34, mounted near the ends of the cylinder. Centrally pivoted on the brackets 33 and 34 are bell crank levers 35 and 36. In the wall of the cylinder 27, near the ends of said cylinder, are openings shaped to form valve seats, in which are mounted inwardly opening valves 38. The valves 38 are provided with stems 39 extending outwardly through the openings in the cylinder wall and pivotally connected to one of the arms of the respective bell cranks 35 and 36. Mounted

on the stems 39, between the bell cranks and the wall of the cylinder, are coil springs 40. In each end of the cylinder 27 is an inwardly opening spring controlled valve, as shown in Fig. 4, which may or may not be employed, as desired. When used, the last described valve simply offers further means for admitting air to the respective ends of the cylinder when a vacuum is created therein. The other arms of the bell crank levers 35 and 36 extend into the path of the stops 32 on the rod 31 in such manner that the operation of the valves is as follows: When the rod 16 is at the limit of its movement as shown in Fig. 1, the rod 31 will have operated on the rod 30 to move the piston 28 toward the portion of the cylinder 27 nearest the track. Assuming that the train approaches on the switch track and strikes the device 22, thereby moving the rod 16 longitudinally to the other limit of its movement, the members 36 and 35 and 32 are so arranged that during the greater part of the movement of the rods 16 and 31, the piston 28 is moved in the cylinder 27 away from the track, compressing the air in the upper end of the cylinder, as shown in Fig. 4. On account of the form of the valves, the air will pass into the lower part of said cylinder, which will remain at little below atmospheric pressure on account of the strength of the spring 40. The springs 40, however, are of sufficient strength to hold the valves seated. The last portion of the movement of the rod 31, however, causes the stop 32 to engage the bell crank 36, thereby unseating the valve 38 and permitting the air to escape from the upper part of the cylinder. Thereafter no ordinary pressure will be sufficient to throw the switch back to its original position on account of the fact that it is necessary, in order to so throw the switch, to compress the air in the cylinder 27 during the movement of the stop 32 from the bell crank 36 to the bell crank 35. On account of the fact that power enough to effect such compression is necessary to throw the switch, it will be seen that the switch is instantly locked in either of its set positions by means of its cylinder and parts connected therewith. The advantage of a device of this kind lies particularly in the fact that a pressure lock is provided whereby the switch is held when thrown to either position and cannot be thrown to the other position without the exercise of strong pressure. The switch is thereby saved from danger that might occur through the acts of meddlers, tramps and so on. The parts of our device are of simple and inexpensive construction and can be readily and easily kept in repair. It will be understood that some changes may be made in the details of the construction of our device without departing from

its essential features, and it is our intent to cover by this application any such changes which may be included within the scope of the following claims:

5 We claim as our invention:

1. In a device of the class described, means for moving the movable rails of a railroad switch, means whereby said moving means may be operated from points on the 10 track spaced apart from said switch, a cylinder adjacent to said switch, a piston slidably mounted therein, and means for connecting said piston with movable rail members, said piston being provided with inwardly opening valves near its ends, and means operated by said piston operating means for unseating one of said valves simultaneously with the latter part of the movement of the movable rail members in 15 either direction.

20

2. In a device of the class described, a bar designed to be secured to the movable rails at a railroad switch, a cylinder, a piston mounted therein, means for operatively connecting said bar with said piston, said cylinder being provided with openings near its ends to form valve seats, inwardly opening valves mounted in said openings, yielding means for holding the valves seated, and means operated by said first means for opening the valve in the compression end of the cylinder at the finish of the movement of said bar in either direction.
